CRUSHER MILL

George W. Borton, Philadelphia, Pa., assignor to
 Pennsylvania Crusher Company, Philadelphia,
 Pa., a corporation of New York

Application December 8, 1949, Serial No. 131,747

3 Claims. (Cl. 241—85)

1

This invention relates to breakers and more particularly to an improvement in the Bradford type of breaker.

It is an object of this invention to provide a Bradford type breaker which crushes by hammer impact and shearing.

It is a further object of this invention to provide a mechanism in which the material is subjected to a hammer fracture and shearing action under conditions limiting the forces applied and predetermining the strength of the impact and shearing action.

Other objects and advantages of this invention will become clear upon reading the following description taken with the accompanying drawings in which:

Fig. 1 is a vertical section of a Bradford type breaker taken on the axis of the driving means; and

Fig. 2 is a vertical section of the breaker taken radially of the rotary hammers on the line 2—2 of Fig. 1.

Fig. 1 shows a crusher composed of a rotatable drum 1 within which is a rotor 2 carrying pivoted hammers 3. Referring to the transverse section (Fig. 2), the drum 1 containing lifting shelves 4 is shown rotating clockwise as viewed from the entrance end for carrying up coal to be broken by dropping. A hammer carrying rotor 2 rotates counterclockwise with its hammers 3 for breaking by impact and shearing the coal in the drum 1. The drum 1 is contained in a casing 5 which as shown in Fig. 1 is provided with an opening in one of its side walls 23 through which the drum 1 and rotor 2 are driven. The cylindrical outer wall of the drum 1 is made up of perforated plates 6 through which particles of coal broken up inside the drum 1 fall out into the casing 5. The casing 5 is provided with a discharge opening 7 at the bottom through which the screened particles are discharged into a suitable receptacle.

A conical feed end 8 is formed on the opposite side of the drum 1 from the driving means and a feed chute 9 extending into the drum 1 projects over the lip of the conical end 8. The lifting shelves 4 are provided with slots 10 for the passage of projections 21 extending from the hammers 3 with predetermined axial clearances 24 and radial clearances 25 as shown in Fig. 1. At the feed side of drum 1 the shelves 4 have unslotted sections 11 which pick up the introduced coal from the conical feed end 8.

In order to provide motion to the crusher parts the drum 1 is mounted on a spider 12

2

which is cast integral with a tubular quill 13 and is mounted at one end in an opening in casting 5. The quill 13 is rotatably mounted in pillow boxes 14 and is chain driven through a sprocket 15 mounted on a second spider 16. Through the spider 16 the rotation of quill 13 turns the drum 1. The hammer-carrying rotor 2 is driven by a spindle 17 supported in the quill 13 by bearings 18 and sleeve 19. Rotary motion for turning the spindle 15 is supplied through a pulley 20 mounted on the opposite end from the rotor 2. As viewed in Fig. 2 the drum 1 is rotated clockwise at a slow rotational speed and the rotor 2 is rotated counterclockwise many times faster than the speed of the drum.

In operation the coal or other material supplied through chute 9 descends into the conical feed end 8 of the drum 1 and is distributed by the rotation of the drum 1. The entrance ends 11 of the lifting shelves 4 pick up this coal and coal that has not yet passed through the screen plate 6 and carry it up and drop it as they reach the top of their path and the dropped coal and other coal from the entrance pass into the hammer area following the entrance space. The hammers 3 moving counter to the lifting shelves 4 strike the coal and reduce it by impact, and projections 21 passing through slots 10 also fracture the lumps of coal between the moving parts with a shearing action. Coal on the shelves 4 is constantly carried to the top of the drum 1 where it falls to the bottom for a repetition of the cycle. Reduction of the particles of the material continues until they reach a fineness sufficient to pass through the holes 22 of the perforated plate 6 and fall out through the outlet 7. As the reduced particles pass through the plate 6 and are removed from the bradmill fresh feed enters the mill through the chute 9.

The size of the largest of the particles discharged is regulated by perforations in the screen plates 6 and the character of the particles is largely determined by the spacings between hammer projections 21 and the shelf slots 10. The distance between the edges of the projections 21 and the slots 10 influences the type of fracture produced by the shearing action between the hammers 3 and shelves 4. The spacing of the hammers 3 from the shelves 4 is adjustable permitting a variation in the shearing action and the size to which particles are reduced by this shearing when caught between the projections 21 and the slots 10.

This invention effects a fracturing of material not only by gravity drop and hammer impact

but also by the shearing of the rotating hammers against the material held by the shelves in clearances 24 and 25. The hammers 3 rotating at a speed of the order of 300 to 800 R. P. M. travel much faster than the counter-rotating drum which rotates at a speed of the order of 18 R. P. M. Consequently the high velocity hammers not only strike the freely falling coal and fracture it by impact but also shear through the masses of coal in front of the shelves. The passage of the hammer projections through the shelf slots exerts a shearing type of crushing action on the material caught between the hammer and the shelf. This shearing, in contrast with the attrition reduction of the grinding against screen plates, gives a clean sharp fracture.

In reduction of material to a predetermined size by fracturing it is advantageous to avoid the production of fines or particles which are smaller than the desired size as these undersize particles are largely wasted. In crushing a material generally more than one fracturing is necessary to reduce the material to the desired size. Limiting the number of fines produced during each fracture of the oversize particles increases the efficiency of the crushing operation with consequent savings in cost and material. This invention achieves a limitation on the production of fines by eliminating attrition. Attrition is avoided in this invention by obtaining the fracturing of the material by impact and shearing rather than grinding the material to be fractured between two surfaces. This elimination of attrition is obtained in part by the radial flexibility of the free swinging hammers 3 which may tilt radially upon encountering more than a predetermined resistance on the shelves 4 and thus do not produce the fracturing which would result if the hammers were rigid.

Another advantage of this invention is provided in the combination of shearing actions obtained from the clearances 24 parallel to the axis of rotation and the substantially radial clearance 25. At the clearances 24 the edges of the hammers 3 and shelves 4 approach each other parallel and even though the free swinging hammer 3 may tilt with relation to the radius of the drum 1 the axial edges remain parallel and the clearances merely enlarge. At the clearances 25 the radial edges of the hammers 3 and shelves 4 approach each other at a sharply shearing angle which may be changed by variations in the tilt of the hammer 3 with relation to the radius of the drum 1 but the amount of the clearances 25 remains constant. These varieties of shearing angles provide different shearing actions both of which fracture by a short period of violent contact rather than by slow continuous grinding.

Where there is likelihood of tramp iron or the like contaminating the supply, the shearing and lifting shelves 4 will preferably be held in radial position by shear bolts secure under the ordinary loading of the worked material but shearing apart

under the impact of excessive pressures developed when pieces of iron or other hard tough material are caught between the hammers and shelves which latter then yield to permit the hammers to pass. The machine is then stopped and the tramp iron removed and the shelves restored with replacement of the safety shear bolts.

It will be understood that the shape of the hammers and the slots may be varied without departing from the principle of impact and shearing. A wide range of materials may be reduced by the above apparatus and while a specific example has been illustrated by the use of coal other substances may be broken up. It is, therefore, intended that the invention not be limited other than by the scope of the appended claims.

I claim:

1. A rotary crusher mill comprising a drum rotatable around a horizontal axis and having opposite heads, a rotor having pivoted hammers within the drum, a separate screen forming the periphery of the drum between said heads, shelf means within said drum comprising strips connecting the drum heads and provided with a plurality of longitudinal series of projections directed inward from said screen and separated from each other by intervening spaces, radially extending edges on the hammers of said rotor passing between and interacting with said projections, means driving said drum and rotor in opposite directions at different speeds to pass said edges through said spaces between said projections so as to fracture material by downward hammer blows in said spaces during the lifting of said material by said shelf means, and means discharging the fragments passing through the peripheral screen.

2. A rotary crusher mill as set forth in claim 1 in which the rotary drum is provided with an enclosing casing and a feed chute at the entrance end of the drum and a discharge at the bottom of said enclosing casing.

3. A rotary crusher mill as set forth in claim 1 in which the pivoted hammers of the rotor are spaced apart at angles different from the angular spacing of the strips of the shelf means so that only a single hammer of the rotor is passing through the strip projections at a given time and the crushing effort is correspondingly divided between the multiplicity of hammer and strip engagements for each rotation of the rotor.
